UNITED STATES PATENT OFFICE.

EDWARD BOYLE, OF LYNDHURST, NEW JERSEY, ASSIGNOR TO MAC CANNON-ALEXANDER CORPORATION, OF NEW YORK, N. Y., A CORPORATION OF NEW YORK.

CASTING MOLD.

Application filed August 8, 1925. Serial No. 48,917.

This invention relates to molds for casting metals and pertains more particularly to molds having interchangeable dies, whereby metal objects of several different shapes

5 may be cast in the same mold.

It is an object of this invention to provide a mold, in which metal objects of the same shape may be cast rapidly and conveniently, and in which the dies for forming various

10 portions of the objects may be replaced and production of a differently shaped object resumed without delay.

Other objects and advantages of the invention will appear hereinafter.

15 A preferred embodiment of the invention selected for purposes of illustration is shown in the accompanying drawings, in which,

20 Figure 1 is a top plan view of the apparatus, the parts of the mold being shown in position for casting.

Figure 2 is a top view of the apparatus, the parts being shown in position for ejecting the work.

25 Figure 3 is a section on the line 3-3 of Figure 1.

Figures 4 and 5 are perspective views of two forms of object adapted to be cast by the mold.

30 Figure 6 is a plan view of one of the mold parts.

In the embodiment of the invention illustrated in the drawings, an apparatus for casting battery straps for electric storage batteries is disclosed, and in the following 35 description particular reference will be made to this type of apparatus, although it will be understood that the invention is susceptible of use in other connections.

Referring to the drawings, the apparatus 40 comprises a base plate 1 having legs 2 adapted to be secured to a table or work bench by means of the screw 3 passing through the feet 4. Part of the base plate 1 is provided with a flat surface 5 which forms in most 45 cases one of the walls of the mold. On the opposite side of the base plate an opening 6 is provided through which the work may be ejected in a manner hereinafter described.

Underneath the surface 5, the base plate is 50 cut away in order to reduce the weight of

the mold, but the ribs 7 remain to reinforce the plate to provide adequate strength, and also serve to some degree to radiate heat to keep the mold at a relatively cool temperature during use.

55 At the back of the base plate 1 is mounted a bolt 8 serving as a pivot or axis about which the two side molds 9 and 10 may swing. Each of the side molds 9 and 10 is provided with an aperture through which the bolt 8 passes and the bolt is provided with a nut 11 to hold it in place.

Each of the side molds 9 and 10 is permitted limited oscillation with respect to

the base plate, movement in one direction 65 being opposed by the abutment 12 and movement in the opposite direction being opposed by the abutment 13 as described more particularly hereinafter.

Each of the side molds is provided with a removable wooden 70 handle 14 by which the sections may be swung as desired by the operator.

Battery straps as ordinarily used in different storage batteries vary considerably in 75 their detail, although nearly all such straps

are of the same general contour. For instance, certain straps are provided with a comb 15 as illustrated in Figure 4, while other batteries require the plain straps 16 as

illustrated in Figure 5. Certain batteries 80 require that the shank 17 be provided with a standard screw thread as illustrated in Figure 4, while others require a square thread, while still others as illustrated in Figure 5 require no thread whatever.

85 It is proposed according to the present invention to provide means by which the dies for forming the straps and their shanks may be replaced by different dies of any desired shape so that any combination of particular strap and particular shank may be produced with a single mold.

90 For this purpose in the embodiment of the invention disclosed herein the side mold 9 is provided with a slot 21 having bevelled 95 sides 22 in which dies 23, which may be formed in any desired shape, may be held. Similarly the side mold 10 may be provided with a slot 24 having bevelled sides 25 in which matching dies 26 may be held. As 100

will be observed, the interior contour of the dies 23 and 26 may be of any desired design, such that standard threads, square threads, or no threads may be formed in the shank 5 of the strap to be cast.

Lying between the bottom face of the side mold 9 and the surface 5 of the base plate 1 is a die 27 loosely secured to the side mold 9 by means of the screw 28 which serves to 10 centralize the plate with respect to the die 26. On the other side of the mold and lying between the bottom face of the side mold 10 and the surface 5 of the base plate is a die 29 centralized with respect to the side mold 10 by means of the screw 30. As will be observed, the die 29 may be removed and replaced as desired by another die having any desired contour for forming the strap in the desired shape, as for instance one die 29 is 20 provided for casting the positive strap and another for casting the negative strap.

In casting battery straps, the operator first determines the characteristics of the particular strap which he wishes to cast, and 25 inserts in the mold die 29 of the desired shape. Thereafter dies 23 and 26 having the desired characteristics may be inserted in the slots 21 and 24. The operator then grasps the handles 14 and closes the sections 9 and 30 10 of the mold and moves the sections in closed position until the section 9 is stopped by the abutment 12. In this position, illustrated in Figure 1, the mold is ready for pouring. After the metal is poured and the 35 work has become set, the handle to the section 9 is moved to the left while the plate or die 27 is held by the abutment 12 which die 27 holds the casting and thus permits the operator to free the casting from the die 40 23. Then the handle of the section 10 is moved to the right until stopped by the abutment 13.

In order to completely free the work from the mold, means are provided to eject the 45 work as the handle 14 is moved to the right to move the side mold 10. For this purpose the die 26 is provided with a plunger 31 passing through an opening 32 in the die and having a head 33 adapted to seat on the 50 shoulder 34. In order to normally hold the plunger in its retracted position the compression spring 35 is provided, one end of which bears against the nut 36 on the outer end of the plunger 31 and the other end of 55 which bears against a washer 37. When the side mold 10 is swung to the right the outer end of the plunger 31 strikes the abutment 13 compressing the spring and forcing the plunger through the die against the work 60 and at the same time the plate or die 29 comes against the lower abutment—so that the casting is freed from the mold 25 and dropped through the opening 6.

By proper manipulation of the handles 14 65 the sections of the mold may again be swung

together and moved to the position shown in Figure 1, in which position the mold is again ready for pouring.

It is to be understood that the invention may be variously modified and embodied 70 within the scope of the subjoined claims.

I claim as my invention:

1. A mold for casting metal objects, comprising, in combination, a base plate having a surface adapted to form one side of said objects, a plurality of side molds pivotally mounted on said base plate, said side molds being provided with interchangeable dies for forming objects of different contours.

2. A mold for casting metal objects, comprising, in combination, a base plate having a surface adapted to form one side of said objects, a plurality of side molds pivotally mounted on said base plate, said side molds being provided with means for receiving and holding interchangeable dies of different 85 shapes.

3. A mold for casting metal objects, comprising, in combination, a base plate having a surface adapted to form one side of said objects, a plurality of side molds pivotally mounted on said base plate, and means for automatically ejecting the work from the mold upon movement of said side molds.

4. A mold for casting metal objects, comprising, in combination, a base plate having a surface adapted to form one side of said objects, a plurality of side molds pivotally mounted on said base plate, said side molds being provided with means for receiving and holding interchangeable dies of different shapes, and means for automatically ejecting the work from the mold upon movement of 100 said side molds.

5. In a mold for casting battery plate 105 straps, in combination, a plurality of side molds, a plurality of dies, means carried by said side molds for removably holding a pair of said dies adapted to form the shank, and separate means carried by said side molds 110 for removably holding a pair of said dies adapted to form a strap, said side molds being separably mounted to permit ejection of the molded article.

6. In a mold for casting battery plate 115 straps, in combination, means including dies for forming the strap, means including dies for forming the shank, and means whereby each of said dies may be removed and replaced by dies of different shape.

7. In a mold for casting battery plate 120 straps, in combination, a base plate, a plurality of side molds pivotally mounted on said base plate, said side molds being provided with slots for holding interchangeable dies 125 for forming part of said strap, and means for removably attaching other dies to said side molds for forming another part of said strap.

8. In a mold for casting battery plate 130

straps, in combination, a base plate, a plurality of side molds pivotally mounted on said base plate, said side molds being provided with slots for holding interchangeable dies for forming part of said strap, means for removably attaching other dies to said side molds for forming another part of said strap, and means for automatically ejecting the work from the mold upon movement of said side molds.

9. In a mold for casting battery plate straps, in combination, a base plate, a plurality of side molds pivotally mounted on said base plate, said side molds being pro-

vided with slots for holding interchangeable dies for forming part of said strap, means for removably attaching other dies to said side molds for forming another part of said strap, a plunger mounted in one of said dies, an abutment mounted on said base plate and adapted to engage said plunger whereby the work is loosened and ejected from the mold upon movement of said side molds into engagement with said abutment.

In testimony whereof, I have signed my name to this specification this 6th day of August, 1925.

EDWARD BOYLE.
